John H. Lemozz

UNITED STATES PATENT OFFICE.

JOHN K. LEMON, OF TOLEDO, OHIO.

BUILDER'S SCAFFOLD.

Specification of Letters Patent No. 27,815, dated April 10, 1860.

To all whom it may concern:

Be it known that I, JOHN K. LEMON, of Toledo, in the county of Lucas and State of Ohio, have invented a new and Improved 5 Scaffold for Building Purposes; and I do hereby declare that the following is a full, clear, and exact description of the same, reference being had to the annexed drawings, making a part of this specification, in 10 which—

Figure 1, is a longitudinal section of a scaffold constructed according to my invention. Fig. 2, is a transverse section of ditto. Fig. 3, an enlarged side sectional view of one 15 of the blocks with its clamp or band.

Similar letters of reference indicate corresponding parts in the several figures.

To enable those skilled in the art to fully understand and construct my invention I 20 will proceed to describe it.

A, represents a series of uprights the lower ends of which have each a base strip *a*, secured to it properly braced. Any proper 25 number of uprights may be used according to the length of scaffold required, the uprights being placed about seven and a half feet apart and about 4½ feet from the wall B, of the building. The uprights A, are of quadrilateral form and of any suitable 30 height and on each upright rectangular metal bands C, are placed. These bands are made of flat bars and the bands are considerably longer than the thickness of the uprights sufficiently so to admit of a wedge-shaped block D, being inserted in them, as 35 shown clearly in Figs. 2, and 3. Each block D, is slotted longitudinally, as shown at *a'*, the slots being parallel with the outer sides of the blocks which are inclined, the inner 40 sides adjoining the uprights being parallel with the latter, and in each band C, a pin or rod *b*, is fitted transversely, said pins or rods passing through the slots in the blocks.

The bands C, it will be seen will retain the 45 blocks D, at any point on the uprights, the blocks when subjected to weight being

forced down and firmly wedged between the bands and uprights. The blocks may be adjusted to any desired point by simply raising them in the bands which movement 50 causes the blocks in consequence of their inclined outer sides to recede from the uprights.

To form the scaffold the lowermost blocks D, are first adjusted on the uprights at a 55 height coinciding with that of the wall B, and the putlogs E, are laid one end on the wall and the other end on the blocks D, as shown clearly in Fig. 2, the flooring plank F, being simply laid on the putlogs without 60 being nailed. When the wall is built up sufficiently to require a second flooring on the scaffold, the uppermost blocks D, are raised on the uprights and secured to them at the proper points the putlogs placed on 65 them and on the top of the wall, and the flooring on the lower putlogs removed and placed on the upper putlogs. By this arrangement the scaffold may be very readily erected and taken down, and increased in 70 height as required with the greatest facility and a very firm and secure scaffold obtained. The pins or rods *b*, fitting in the slots *a'*, of the blocks serve to keep the bands and blocks together, and when the blocks are moved up 75 or down, the slots allow of such movement without disturbing the position of the bands. Thus the blocks may be driven down more firmly whenever desired by blows upon their upper ends without moving the bands. 80

Having thus described my invention what I claim as new and desire to secure by Letters Patent, is—

The employment of the slotted wedge blocks D, in combination with bands C, pins 85 *b*, and uprights A, as and for the purpose herein shown and described.

JOHN K. LEMON.
